AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

LUBRICATING DEVICE.

1,339,619.

Specification of Letters Patent. Patented May 11, 1920.

Application filed September 29, 1919. Serial No. 327,197.

To all whom it may concern:

Be it known that I, AUGIE L. HANSEN, a citizen of the United States, and a resident of Evanston, in the county of Cook, State 5 of Illinois, have invented certain new and useful Improvements in Lubricating Devices, of which the following is a specification.

My invention relates to lubricating devices and particularly to oil cups of the splash feed type.

Among the important objects of my invention are: to provide improved construction and arrangement for readily permitting an oil bearing cup part to be applied to or removed from a nipple member which is permanently secured to conduct oil to the surfaces to be lubricated; to provide improved and more efficient means for detachably securing the cup and nipple members together; to provide improved arrangement for permitting the removed inverted cup member to be readily filled with oil, and improved means for preventing escape of the oil when the cup is returned to upright position; to provide improved construction and arrangement whereby when the cup is applied to the nipple member, pressure will be introduced into the cup and a charge of oil forced therefrom to be delivered to the bearing surfaces, thus insuring immediate lubrication service to the bearings after they have been cleaned or first put into use; to provide improved and more efficient means for feeding and conducting oil into the discharge passageway of the cup; to provide improved arrangement which permits adjustment to be readily made for speed of oil flow from the cup; and in general, to provide a simple, practical and efficient lubricating device of the class referred to.

On the accompanying drawings I show a lubricating device which embodies the above and other features of my invention. On 45 these drawings,

Figure 1 is a side elevational view of the device,

Fig. 2 is an enlarged elevational view with the cup shell in vertical diametral section,

50 Fig. 3 is an enlarged view showing all the parts in section and

Fig. 4 is a sectional view on plane 4—4, Fig. 3.

The nipple member of the device comprises the threaded plug section 5, the polygonal wrench receiving head 6 and the spindle 7 extending upwardly from the head. The axial passageway 8 extends upwardly through the plug and head sections and a distance upwardly through the spindle 7, 60 lateral passageways 9 through the spindle communicating with the vertical passageway 8. The section *a* above the lateral passageways 9 is of slightly less diameter than that of the base section *b* of the spindle. 65 The upper end *c* of the spindle is externally threaded and below this threaded end the diameter is reduced to form the frusto conical section *d* between the threaded end and the section *a*. In the top of the head 6 is the 70 annular groove 10 in which a washer 11 of suitable material such as fiber is seated.

The cup is constructed of sheet metal and comprises the cylindrical body part 12, the dome shaped top 13 integral therewith, and 75 the bottom 14. This bottom has the outer flange 15 which when inserted snugly fits in the body part 12. It also has the inner annular upstanding flange 16 surrounding the central opening 16' which receives the lower 80 end of the tube 18, the tube being secured at its lower end to the bottom by means of the flange 16 and extending upwardly centrally through the cup member into engagement at its upper end with the top 13 when the 85 bottom 14 is inserted, the tube being secured to the bottom before the bottom is inserted into the cup body. The tube is of substantially uniform diameter both internally and externally and snugly fits the base *b* of the 90 nipple member, it having the vent holes 17 which, when the cup member is applied to the nipple member, are just above the flange 16 to be in communication with the interior of the cup at certain times.

The upper end of the tube is internally threaded to receive the threaded end *c* of the nipple member, such threaded connection drawing the base of the cup member against the washer 11 to effect a sealing fit. 100 To insure secure threaded engagement and to prevent self loosening of the cup member,

the upper end of the tube is preferably bifurcated and the two opposed semi-circular sections *e* and *f* bent inwardly a distance after they have been threaded. With this arrangement the ends are forced apart when receiving the threaded end *c* of the spindle and their spring force then holds the tube securely locked to the spindle and the cup securely held with sealing engagement on the nipple member. To facilitate turning of the cup member, it has the knurled belt 18.

Surrounding the tube 18 and reciprocable thereon is the cylindrical sleeve 19. The sleeve is of such length that its upper end 15 will be below the oil inlet openings 20 of the tube 18 when the cup is in upright position. These inlet openings 20 may be at any point at the upper end of the tube, but as shown, they are formed by enlarging the lower ends 20 of the slots between the bifurcation ends *e* and *f*. The upper end of the sleeve 19 is of enlarged diameter to form the annular cup or pocket 21, and at opposite sides at this pocket the sleeve is cut away to leave 25 clearance or entrance passageways 22.

Describing now the operation, the nipple member is screwed into a supporting frame *F* to register its outlet passageway 8 with the duct 23 which leads to the bearing surfaces to be lubricated. To fill the cup member, it is inverted and oil charged thereinto through the tube 18. When the cup is inverted, the sleeve 19 will be against the top 13 and the air vent openings 17 will be exposed and will connect the interior of the cup with the exterior thereof. As the oil flows downwardly in the tube 18, it enters the cup through the openings 20. If the passageways 22 of the sleeve are not opposite the openings 20, then the oil flows into and through the pocket 21 until it reaches the passageways 22 from where it flows into the cup. During such inflow of oil, the displaced air can flow to the exterior through 40 the vents 17. The cup is not entirely filled as after filling the oil level should be below the openings 20 to prevent direct flow of oil from the cup. The filled cup can now be inserted and the sleeve 19 dropping down 45 against the base 14 will cover the vent holes 17 so that the oil cannot escape from the cup through these holes. The cup is then applied to the spindle 7, and the passage of the spindle through the tube 18 will displace 50 any oil therein and this oil will flow downwardly through the annular space *s* between the spindle and tube and through the passageways 9 and 8 into the duct 23 and to the bearing surfaces.

60 Thus when a cup is applied to a bearing surface which has not before been lubricated or after a bearing surface has been cleaned, the application of a filled cup will cause a charge of oil to be delivered which will be 65 ample to cover the bearing surfaces.

My improved cup is designed to be particularly useful in connection with vehicles such as automobiles, where the jarring and jolting will cause the oil to be thrown upwardly and fed gradually to the bearing surfaces. The sudden vertical displacements of the cup cause the oil to be flung upwardly and part of it enters the openings 20 which are adjacent the frusto conical section *d* of the spindle, the oil entering the 75 enlarged space *g* and then gradually flowing down the capillary space *s* into the passageways 9 and then through the passageway 8 to the bearing surfaces. Some of the oil splashes from the cup into the pocket 21 of 80 the sleeve 19, or against the tube 18 at the passageways 22. This oil is lifted as the sleeve 19 is reciprocated by the jolting and conducted to the openings 20, the sleeve acting somewhat like a pump plunger to raise 85 the oil so that it may flow through the openings 20. The sleeve therefore performs two functions, namely to close the air vents 17 when the cup is in upright position and disconnected from the nipple structure, and 90 to act as a plunger for carrying oil to the outlet openings 20.

The speed of oil feed from the cup is determined by the thickness of the capillary space *s* between the spindle and tube. The 95 enlarged space *g* acts as a reservoir to receive oil from the openings 20 but the oil flows from the reservoir slowing down the capillary space to the passageways 9. If it is desired to increase the speed of flow, then 100 the diameter of the section *a* of the spindle would be correspondingly increased to increase the thickness of the capillary space and therefore reduce the resistance to flow therethrough. At its lower end the tube 105 18 snugly fits the base *b* of the spindle and oil cannot escape. In case any oil should succeed in working its way downwardly at this point, the sealing engagement of the cup's bottom with the washer 11 would 110 prevent escape of the oil. The engagement of the tube 18 with the section *b* of the stem also closes the air vent holes 17 so that the sleeve 19 is relieved of this duty when the cup has been applied to the nipple member. 115

The device would of course operate more or less efficiently with the sleeve 19 omitted, but then the cup could not be set in upright position as the oil would escape, but would have to be applied immediately 120 to the nipple, the section *b* of the spindle closing the vent openings. However, the sleeve 19 permits the cup to be set down in upright position after filling thereof or at any other time without leakage, and the 125 sleeve also assists in carrying oil to the outlet openings 20 when the cup structure is reciprocated.

In some oiling devices, felt or other material has been interposed in the path of the 130

oil to retard its flow. Such retardation is not uniform and therefore unreliable. In my improved construction, the oil is being continually thrown in the reservoir or funnel space *g* at the upper end of the tube 18, but its flow from such reservoir to the nipple passageway is retarded by the restricting or capillary space *s*. Such retardation is uniform and constant so that the feed of oil 10 into the bearing surface is uniform.

In do not, of course, desire to be limited to the exact construction, arrangement and operation shown and described as changes could readily be made without departing 15 from the spirit and scope of the invention.

I claim the following:

1. In a lubricating device, the combination of a nipple having a passageway therethrough, a spindle extending from said nipple, the upper end of said spindle being threaded, a cup having a closed bottom, a tube extending substantially from said bottom to the other end of the cup and threaded at such other end to receive said threaded 25 spindle whereby to lock the cup with its bottom against said nipple, openings at the upper end of said tube, and passageway connecting between said openings and said nipple passageway.

2. In a lubricating device, the combination of a nipple having a passageway therethrough, a spindle extending from said nipple and having its outer end threaded, a cup member having a closed bottom, a tube 35 extending from said bottom upwardly in said cup, said tube opening to the exterior at its lower end for receiving said spindle, the upper end of said tube being threaded to receive the threaded end of the spindle 40 whereby to secure the cup to the nipple, there being capillary space between said tube and spindle, the upper end of said tube having an opening connecting said space with the cup interior, the other end of said space 45 being connected through said spindle with the nipple passageway.

3. In a lubricating device, the combination of a nipple having a passageway therethrough, a spindle extending upwardly from 50 said nipple, a cup having a bottom, a tube extending centrally through said cup and through said bottom to be open to the exterior at its lower end to receive said spindle, the upper end of said spindle being threaded and the upper end of said tube being likewise threaded in order to receive the spindle thereby to secure said cup to the nipple, the lower section of said spindle snugly receiving said tube and the section 55 of the spindle above said lower section being of slightly reduced diameter to leave a capillary space between the spindle and the tube, said nipple passageway being continued a distance through said spindle, said 60 spindle having lateral passageways connect-

ing said continued passageway with said capillary space, and openings to the upper end of said tube, connecting said capillary space with the cup's interior.

4. In a lubricating device of the class 70 described, the combination of a nipple having a passageway therethrough, a spindle extending from said nipple, a cup having a closed bottom, a tube extending upwardly through said cup from said bottom and 75 open to the exterior at its lower end for receiving said spindle, threaded engagement between said tube and spindle for securing said cup on said nipple, and means for conducting lubricating fluid through said 80 tube and to said nipple passageway.

5. In a lubricating device of the class described, the combination of a nipple, a spindle extending from said nipple, a passageway through said nipple and partly through 85 said spindle and communicating with the exterior of the spindle, a cup, a tube extending through said cup from its bottom, said tube being open at its lower end to the cup exterior whereby it may be slipped 90 down over said spindle and said cup supported on said nipple, the upper end of the said tube having entrance opening for lubricating fluid, and restricted passageway between said tube and spindle for retarding 95 the flow of fluid from the tube entrance to the spindle and nipple passageway.

6. In a lubricating device of the class described, the combination of a nipple, a spindle extending therefrom, a passageway 100 through said nipple and spindle, inlets to said passageway from the exterior of said spindle, a cup, a tube extending centrally through said cup from the bottom thereof and open at its lower end for receiving said 105 spindle whereby said cup may be seated on said nipple, a reservoir in the upper end of said tube, there being openings in said tube connecting said reservoir with the cup interior whereby oil may flow into said reservoir, and a restricted passageway between 110 said tube and spindle from said reservoir to the nipple passageway inlet.

7. In a lubricating device of the class described, the combination of a nipple, a 115 spindle extending from said nipple, a passageway through said nipple, and inlets thereto from the sides of said spindle, a cup, a tube extending through said cup from the bottom thereof, said tube being open at its 120 lower end to the cup exterior whereby said cup may be slipped down over said spindle, the upper end of said tube being open to the cup's interior whereby to receive oil from the cup, the diameter of said spindle being 125 such as to leave only a restricting passageway between the upper end of said tube and the nipple passageway inlets whereby the flow of oil is retarded.

8. In a lubricating device of the class 130

described, the combination of a nipple, a spindle extending from said nipple, a cup having a closed bottom, a tube extending through said cup from said bottom and open at its lower end to receive said spindle, a passageway through said nipple open to the tube interior, said tube being open at its upper end for the flow of oil thereinto from the cup's interior, means for retarding the flow of oil through said tube to the nipple passageway, and air vent openings through said tube which are closed by said spindle when said cup receives said spindle.

9. In a lubricating device of the class described, the combination of a nipple, a spindle extending therefrom, a cup having a closed bottom, a tube extending through said cup from said bottom and having its lower end open for the reception of said spindle, means for securing said cup on said nipple, said nipple having a passageway open to the tube interior, the upper end of said tube being open to the cup interior, and air vent holes in said tube closed by said spindle when the cup is secured on said nipple.

10. In a lubricating device of the class described, the combination of a nipple having a passageway therethrough, a cup having a closed bottom, a tube extending through said cup from said bottom, a spindle extending from said nipple for receiving said tube, the upper end of said spindle being threaded, the upper end of said tube having threaded bifurcated ends for clampingly receiving said spindle end, said tube being open for the flow of oil therethrough to the nipple passageway.

11. In a lubricating device of the class described, the combination of a nipple, a spindle extending therefrom, a cup having a closed bottom, a tube extending through said cup from said bottom for receiving said spindle at its lower end, means for securing the cup to the nipple, said nipple having a passageway and the upper end of said tube being open to the cup interior for the flow of oil therefrom to said nipple passageway, air vent holes at the lower end of said tube closed by said spindle when the cup is secured to the nipple, and a sleeve surrounding and reciprocable on said tube for closing said air vents when said cup is detached from said nipple.

12. In a lubricating device of the class described, the combination of a nipple, a spindle extending therefrom, a cup having a closed bottom, a tube extending through said cup from said bottom for receiving said spindle at its lower end, means for securing the cup to the nipple, said nipple having a passageway and the upper end of said tube being open to the cup interior for the flow of oil therefrom to said nipple passageway, air vent holes at the lower end of

said tube closed by said spindle when the cup is secured to the nipple, and a sleeve surrounding and reciprocable on said tube for closing said air vents when the cup is detached from said nipple, said sleeve acting as a plunger for carrying lubricating fluid to the upper end of said tube.

13. In a lubricating device of the class described, the combination of a nipple, a spindle extending therefrom, a cup, a tube extending through said cup and open at its lower end to receive said spindle, the upper end of said tube being open to the cup's interior, said nipple having a passageway open to the tube interior, and a sleeve reciprocable on said tube and operable to lift lubricating fluid to and into the upper end of said tube.

14. In a lubricating device of the class described, the combination of a nipple having a passageway therethrough, a cup having a closed bottom, a tube extending through said cup from said bottom, means for securing said cup on said nipple with the lower end of the tube in communication with the nipple passageway, said tube being open at its upper end to the cup interior, and a sleeve surrounding said tube and reciprocable thereon, said sleeve operating to carry oil to the upper end of said tube. 95

15. In a lubricating device of the class described, the combination of a nipple having a passageway therethrough, a cup, a tube extending through said cup from its bottom and open at its lower end, means for securing said cup on said nipple with the tube in communication with the nipple passageway, the upper end of said tube being open to the cup interior, a sleeve surrounding and reciprocable on said tube, and an oil carrying pocket at the upper end of said sleeve, oil splashing into said sleeve during jolting of the cup and said oil being delivered to the tube when said sleeve is raised.

16. In a lubricating device of the class described, the combination of a nipple having a passageway therethrough, a cup having a closed bottom, a tube extending from said bottom through said cup, a spindle extending from said nipple and adapted to receive said tube, said nipple passageway continuing through said spindle and opening into the tube interior, the upper end of said tube being open to the cup interior, air vent holes in said tube closed by said spindle 120 when the cup is on said nipple, and a sleeve surrounding and reciprocable on said tube, said sleeve when in lower position closing said air vent openings and when in upper position delivering lubricating fluid into 125 said tube.

17. In a lubricating device of the class described, the combination of a nipple having a passageway therethrough, a cup, a tube extending through said cup from the 130

bottom thereof, means for securing said cup on said nipple with said tube in communication with the nipple passageway, air vent holes through the tube in the lower end thereof, and a sleeve surrounding and reciprocable on said tube, said sleeve when in lower position closing said air vent holes

and during its upward movement serving to carry lubricating fluid into said tube.

In witness whereof I hereunto subscribe 10
my name this 24th day of September, A. D.
1919.

AUGIE L. HANSEN.
